UNITED STATES PATENT OFFICE.

SAINTEME DIOLOT, OF NEW YORK, N. Y.

DESIGN FOR CLOCK DIAL AND HANDS.

SPECIFICATION forming part of Design No. 14,162, dated August 14, 1883.

Application filed June 7, 1883. Term of patent 14 years.

To all whom it may concern:

Be it known that I, SAINTEME DIOLOT, of the city, county, and State of New York, have invented and produced a new and original Design for Clock Dials and Hands, of which the following is a full, clear, and exact description.

The object of my invention is to provide a new, original, and handsome design for clock dials and hands.

Reference is to be had to the accompanying drawing, forming part of this specification, in which a face view of my newly-designed clock dial and hands are shown.

The clock-casing A is made in the shape of a tambourine, provided with the usual head, B, forming the dial-plate. The casing is provided with the bells or cymbals C, as in tambourines. In place of the numerals provided on usual dials, I have provided a wreath composed of twelve different flowers, produced on the head B or dial-plate. For instance, the rose *a* represents 12; the morning-glory *b*, 1; the poppy *c*, 2; the fuchsia *g*, 6; the narcissus *j*, 9; the honeysuckle *k*, 10; and so on. The flowers are to be represented as being united by twigs, &c., to form a wreath, but can be arranged separately, if desired. They can be produced in one or different colors, and can be printed, drawn, embossed, or engraved, as may be desired.

I do not limit myself to the flowers named, but may use any flowers, and may arrange them according to their symbols.

The hands D E are made to represent twigs or branches, and a butterfly or other insect, F, is preferably fastened on the end of each hand, so that it will appear as if the butterflies or insects were creeping or flying over the flowers, as the said hands continually change their positions.

I claim—

1. The herein-described design for the dial of a clock, consisting of a plate provided with twelve flowers in place of the usual figures or numerals, substantially as set forth. 45

2. The herein-described design for the dial of a clock, consisting of a plate provided with a wreath of flowers in place of the usual figures or numerals, substantially as set forth. 50

3. The herein-described design for a clock dial and hands, consisting of a plate provided with a wreath of flowers, and hands made in imitation of twigs or branches, substantially as set forth. 55

4. The herein-described design for a clock dial and hands, consisting of a plate provided with a wreath of flowers, and hands made in imitation of branches or twigs carrying insects, substantially as set forth. 60

5. The herein-described design for the hands of a clock, consisting of branches or twigs carrying insects, substantially as set forth.

SAINTEME DIOLOT.
